UNITED STATES PATENT OFFICE.

JOSEPH H. KOSEK AND RAYMOND B. TRAUTMAN, OF MINNEAPOLIS, MINNESOTA, AS
SIGNORS TO DAVID W. DORRANCE, OF MINNEAPOLIS, MINNESOTA.

ARTIFICIAL LIMB.

Application filed September 10, 1925. Serial No. 55,503.

Our invention relates to improvements in artificial limbs and particularly to hands of that general nature disclosed in Patent No. 1,042,413 granted Oct. 29, 1912 to David W.

5 Dorrance.

An object of the present invention is to provide a simple and durable device adapted to be applied to the conventional arm stump socket and having co-operating bowed fingers, 10 which are yieldingly brought together and normally held closed, said fingers being adapted to be opened by means of the usual pull cord customarily employed for such purpose.

Another object is to provide improved finger tip members in an article of the present nature, which members adapt the article for many and varied operations simulating the use of the fingers of the human hand.

With the foregoing and other objects in view, which will appear in the following description, the invention resides in the novel combination and arrangement of parts and in the details of construction hereinafter described and claimed.

25 In the drawings, Fig. 1 is a perspective view of a device embodying our invention; Fig. 2 is a side view thereof, a portion of the same being broken away to plainly show structural parts that otherwise would be concealed; and 30 Fig. 3 is a fragmentary perspective view, the same particularly illustrating the finger tip members of the co-operating fingers.

Referring to the drawings, it will be noted that our improved article includes a shank 35 A, finger frame B and fingers 10, 11. The shank A is a comparatively short piece bowed medially thereof as at 12, and formed at its tip with a cross-head *a*. The butt of the shank A is of conventional design, said butt 40 being threaded and formed with a wrist disk 13 thereon. As usual, said threaded butt is fitted into the head-plate 14 of an arm stump socket 15, the disk 13 being turned against a resilient washer inset in said head-plate 14.

45 The finger frame B comprises two side plates 16 formed integrally at the corresponding ends thereof with the butt of the finger 10. This frame B is pivoted to the end 17 of the cross-head *a* by means of a pintle 18, said cross-head being closely embraced between the side plates 16 of said frame B and thereby adapted to prevent relative movement between frame and shank except about the axis of said pintle 18. The finger 11, carried 50 at the butt thereof between the side plates

16, is pivoted to said plates by means of a pintle 19, the inner edge of said finger being cut out as at 20 to form a bay in which the end 21 of the cross-head *a* plays and also to provide a lug 22 for engagement with said cross-head portion at the rear thereof. The fingers 10, 11 are oppositely bowed to admit of the insertion of objects therebetween, and said fingers have matching hook-shaped tip members 23 that are brought together face to face when said fingers are closed. Means for yieldingly closing the fingers 10, 11 resides in a rubber band 24 or other suitable contracting medium interposed between the shank A and a projection 10^a at the butt of the finger 10. This band, in the absence of resistance, operates to swing the finger frame B forwardly on the shank A and through such action causes the engagement of the lug 22 with the cross-head portion 21, the result being that the finger 11 is swung closed with the tip member 23 thereof implanted against the companion tip member 23 of the finger 10. The finger 11 is formed with a right angular lever 11^a to which the usual pull cord 25 is attached. Said cord being anchored to a user's shoulder operates, upon a forward thrust of the stump socket 15, to exert a rearward pull upon the lever 11^a. A dual effect results from such actuation of the lever 11^a, the finger 11 being swung on the frame B and said frame swung on the shank A. With the parts thus 55 relatively swung the fingers 10, 11 are spread apart and the tip portions 23 spaced as desired. In this connection it will be noted that an opening swing of the finger 11 on the frame B cannot be imparted to said finger in the absence of a compensating swinging movement of the frame B on the shank A. This condition prevailing the fingers 10, 11 are held closed against any force operating 60 equally against said fingers. For example, assume that the user is carrying a bucket with the bail (26, Fig. 2) thereof between the two fingers 10, 11. Any tendency of the bail to spread the fingers apart is directed equally against said fingers, that force working against the finger 10 tending to keep the frame B from swinging on the shank A and thereby securing the finger 11 against an 65 opening swing on said frame. Further countering the finger opening movement of the frame B on the shank A is the rubber band 24 and still further countering such movement of said frame under weight sustained be- 70

75 80 85 90 95 100 105 110

tween the fingers, is the tendency of said frame to swing in finger closing direction, due to the "off center" connection between shank A and finger frame B. In this connection it will be noted that the pintle 18 lies considerably to one side of a plane passing through the axis of the shank A and between the tip members 23 of the fingers 10, 11, the effect of such arrangement being to convert 10 force of a carried load into a force assisting the band 24 in holding the frame B in finger closing relation with respect to the shank A.

The flattened hook-like tip members 23 formed at the free ends of the fingers 10, 11 15 are disposed at right angles to the plane of the finger frame B. The free end of each finger merges into the head of its respective tip member. One of said tip members 23 is fitted at the head thereof with a pair of spaced pins 27, which are arranged to be sheathed within 20 complementing apertures 28 in the head of the other tip member 23, when the fingers are closed. These pins 27 co-operate with each other and with the bodies of the tip members 23 to hold articles (Fig 3) in the grasp of the device and the rear pin 27 aside from its co-operation with said tip members additionally cooperates with the finger frame B to secure articles within the device. This latter 25 method of co-operation between parts is not shown, but it will be readily understood that a case knife may be held with the blade thereof gripped between the bodies of the tip members 23 and the handle resting on the upper frame plate 16. A knife thus disposed has the rear pin 27 as rest for the upper edge of the blade and said upper frame plate 16 as a rest for the lower edge of the handle.

Due to the peculiar co-ordination and arrangement of parts, our improved device is 40 extremely useful for many and varied purposes. It is easily operated to open and close the fingers and said fingers in numerous uses of the device powerfully resist any tendency 45 to open, except by means of the finger opening cord.

Changes in the specific form of our invention, as herein disclosed, may be made within the scope of what is claimed without departing from the spirit of our invention.

Having described our invention, what we claim as new and desire to protect by Letters Patent is:

1. In an article of the class described, a 55 shank for attachment at the butt thereof to an arm stump socket, said shank having a cross-head at its tip, a frame, oppositely bowed complementary fingers carried at opposite ends of said frame, one of said fingers being 60 pivoted thereon and co-operating with one end of said cross-head, the other end of the cross-head being pivoted to the frame, the joint between cross-head and frame being substantially removed from the axis of said 65 shank, tip members, one for each finger, said

members meeting in a plane intersecting said axis, the co-operation of said cross-head with the pivoted finger serving to close said pivoted finger against its companion finger upon swinging movement of the frame in one direction with respect to said shank, yielding contracting means operating between the shank and frame for swinging the latter on the former in said finger closing direction, and a lever on said pivoted finger for imparting an opening swing thereto and for concurrently imparting a compensating finger freeing swing of the frame on said shank.

2. In an article of the class described, a 70 shank for attachment at the butt thereof to an arm stump socket, said shank having a cross-head at its tip, a frame comprising spaced frame bars, the same closely embracing said cross-head and pivoted thereto at one end thereof, a finger carried by said 75 frame, at the end thereof adjacent the joint between frame and shank, a complementary finger pivoted on the opposite end of said frame, said finger having a lug thereon for engagement with the corresponding end of 80 the cross-head, the co-operation of said cross-head with said lug serving to close said pivoted finger upon swinging movement of the frame in one direction with respect to said frame, yielding contracting means operating 85 between the shank and frame for swinging the latter on the former in said finger closing direction, and a lever on said pivoted finger for imparting an opening swing there- 90 to and for concurrently imparting a compensating finger freeing swing of the frame on said shank.

3. In a device of the character described, a 95 shank for attachment to an arm stump socket, a frame pivoted on said shank, a finger 100 on said frame and a complementary finger pivoted thereon, said pivoted finger and shank co-operating, one with the other, the pivoted finger being caused by the shank to close against its companion finger upon the 105 swinging of the frame in one direction on the shank, yielding means interposed between said frame and shank for swinging the former in said finger closing direction upon the latter, and means associated with the pivoted 110 finger for imparting an opening swing there- 115 to and concurrently imparting a compensating finger freeing swing to the frame on said shank.

4. In an article of the class described, a 120 shank for attachment to an arm-stump socket, complementary fingers supported by said shank, said fingers having matching hook-like tip members adapted to close together face-to-face, the free end of each finger merging into the head of its respective tip member, a protuberance extending outwardly beyond the face of one member at the head thereof, the head of the other member being recessed to receive it, and a second protuber- 125 130

ance extending outward beyond the face of one of said members at its head portion, the other member being recessed to receive the same.

5. In an article of the class described, a shank for attachment to an arm-stump socket, a frame on said shank and oppositely bowed, complementing fingers on said frame, said fingers having tip members adapted to close together face-to-face, said members being disposed at right angles to the plane of said frame, and a pin on one tip member, the other member having a complementing aperture to receive it.

15. 6. In an article of the class described, a shank for attachment to an arm-stump socket, complementary fingers supported by said shank and adapted to close, one against the other, a protuberance on one finger tip, the tip of the other finger having a complementing recess to receive the same, and a second protuberance on one of said finger tips, the tip of the other finger having a complementing recess to receive the same, said protuberances being adapted to receive an implement therebetween.

7. In an article of the class described, a shank for attachment to an arm stump socket, complementary fingers carried by said shank, said fingers having matching hook members adapted to close face to face, a protuberance extending from the face of one member, the head of the other being formed with a recess to receive said protuberance, said protuberance being adapted to lie within said recess upon partial opening of said matched hook members to form an abutment for an implement held therebetween.

8. An artificial hand for attachment to an arm stump socket, the same including a frame and a pair of complementing relatively movable fingers carried thereby, said fingers having matching hook members adapted to close face-to-face, and a protuberance on one of said members extending toward the other hook member and supplying a rest for instruments grasped between said hook members.

9. In an article of the class described, a shank for attachment to an arm stump socket, a frame movably mounted on said shank, a pair of complementary fingers on the frame, one being pivoted thereon and co-operating

with said shank, said pivoted finger being swung toward the other finger upon movement of the frame in one direction on said shank, yielding tension means for so moving said frame, and means connected with the pivoted finger for swinging the same away from its complementary finger against the action of said tension means.

55 10. In an article of the class described, a shank for attachment to an arm stump socket, a frame movably mounted on said shank, a pair of complementary fingers on the frame, one being pivoted thereon and co-operating with said shank, said pivoted finger being swung with respect to the other finger upon movement of the frame on said shank, and means for moving said frame on the shank to swing said pivoted finger.

60 11. In an article of the class described, a support for attachment to an arm stump socket, complementary fingers carried by said support, said fingers having complementary face portions thereon, members formed on said face portions providing spaced shoulders extending outwardly beyond the face portions, said face portions being adapted to contact one with the other between said members upon the closing of the fingers and, upon the partial opening of said fingers, to engage, between said members, the opposite sides of an implement, said members in such relation of said fingers serving to engage other opposite sides of such implement.

65 12. In an article of the class described, a support for attachment to an arm stump socket, complementary fingers carried by said support, said fingers having complementary face portions, a member formed on one of said face portions providing a shoulder extending outwardly beyond said face portion, said face portions being adapted to contact one with the other upon the closing of the fingers and, upon the partial opening of said fingers, to engage opposite sides of an implement, said member in such relation of said fingers serving to engage another side of such implement.

70 75 80 85 90 95 100 In testimony whereof, we have signed our names to this specification.
